UNITED STATES PATENT OFFICE.

BERNARD HENRY KARMEN, OF NEW YORK, N. Y.

POWDER-PUFF.

1,270,739.

Specification of Letters Patent. Patented June 25, 1918.

Application filed December 29, 1917. Serial No. 209,461.

To all whom it may concern:

Be it known that I, BERNARD H. KARMEN, a citizen of the United States, and a resident of the city of New York, borough of Manhattan, in the county and State of New York, have invented a new and Improved Powder-Puff, of which the following is a full, clear, and exact description.

This invention relates to powder puffs and it has for its general objects to improve and simplify the construction of devices of this character so as to be comparatively easy and inexpensive to manufacture and at the same time produce a better made and stronger article.

A more specific object of the invention is to provide a machine-made powder puff in which the sewing of the facing material to the back is dispensed with.

Still another object is to provide a novel grip or finger-hold and means for fastening it in the body of the puff.

With such objects in view, and others which will appear as the description proceeds, the invention comprises various novel features of construction and arrangement of parts which will be set forth with particularity in the following description and claims appended hereto.

In the accompanying drawing, which illustrates one embodiment of the invention and wherein similar characters of reference indicate corresponding parts in all the views,

Figure 1 is a perspective view of the powder puff;

Fig. 2 is an enlarged transverse section;

Fig. 3 is a perspective view of the washer or disk on the back of the body;

Fig. 4 is a perspective view of the disk and the ribbon that forms the grip-piece or handle; and

Fig. 5 is a perspective view of the parts that go to make up the face of the puff.

Referring to the drawing, 1 designates the pile cloth or face of the powder puff, 2 the cloth back, and 3 the finger-piece, handle or grip. The cloth pieces 1 and 2 are cut as disks and they are applied around a body which is composed of two telescoping metal sections 4 and 5, the edges of the cloth pieces 1 and 2 being clamped between the interfitting flanges 6 and 7 of the sections 4 and 5. This assembling is done by special dies which have no pressing or distorting effect on the pile face of the puff. The ring sec-

tion 5 leaves the middle of the cloth 1 free and yielding.

The handle piece 3 is made by a piece of ribbon 8 as shown in Fig. 4, which is doubled on itself and passed through a celluloid or other washer 9 which has crossing slits 10 at its center so as to form barbs 11 which bite into the ribbon and prevent the washer from pulling off, the washer serving to give an attractive finish to the back of the puff. The free ends of the ribbon are passed through the center of the cloth back 2 and pass under the section 4 of the body, and the extremities of the ribbon are glued to the outer surface of the section 4 so as to be held properly in place during the assembling. When the parts of the body are assembled the ends of the ribbon are clamped between the flanges 7 and 8, together with the edges 75 of the cloth pieces 1 and 2, and when thus secured the ribbon cannot be pulled out.

A powder puff constructed in this manner can be easily and quickly made and at a minimum expense and the parts cannot tear out, since they are clamped between interfitting body sections.

From the foregoing description, taken in connection with the accompanying drawing, the advantages of the construction and method of operation will be readily understood by those skilled in the art to which the invention appertains, and while I have described the principle of operation, together with the article which I now consider to be the best embodiment thereof, I desire to have it understood that the article shown is merely illustrative and that such changes may be made when desired as fall within the scope of the appended claims.

Having thus described my invention, I claim as new and desire to secure by Letters Patent:

1. A powder puff comprising a body composed of two flanged sections having their flanges telescoping, a pile cloth piece stretched over one section, a back cloth piece stretched over the other section, the edges of the cloth pieces entering between the flanges in the same direction and clamped between 100 such flanges, and a handle connected with the said body.

2. A powder puff comprising a body composed of two flanged sections having their flanges telescoping, and a pile cloth piece attached to the body, one section having a central aperture, a ribbon disposed within

the body and having a doubled portion extending out of the said aperture, and the ends of the ribbon being clamped between the flanges of the said sections.

5. 3. A powder puff comprising a body composed of two flanged sections having their flanges telescoping, a pile cloth piece stretched over one section, a back cloth piece stretched over the other section, the edges 10 of the cloth pieces being clamped between the flanges, and a handle formed by a ribbon doubled on itself and passing through the back cloth piece and the associated section of the body, and the ends of the ribbon 15 being clamped between the said flanges.

4. A powder puff comprising a body composed of two flanged sections having their flanges telescoping and one section having a large opening in its bottom, a pile cloth 20 piece stretched over the section having the opening, a back cloth piece, the edges of the

cloth pieces being clamped between the flanges, a handle formed by a ribbon doubled on itself and passing through the back cloth piece and the associated section of the body, 25 and the ends of the ribbon being clamped between the said flanges, and a washer arranged adjacent the back cloth piece and perforated for receiving the looped portion of the handle ribbon, the edges of the perforation being formed with teeth to bite into the ribbon.

5. A powder puff comprising a body, a doubled ribbon extending into the body and anchored therein, the doubled portion forming 30 a handle, and a perforated disk through which the handle projects, the edge of the perforation being formed with teeth to bite into the ribbon whereby the disk is anchored thereon.

BERNARD HENRY KARMEN.
